UNITED STATES PATENT OFFICE.

FREDERICK H. SCHWARK, OF BONFIELD, ILLINOIS.

CORN-SHOCK COMPRESSOR.

SPECIFICATION forming part of Letters Patent No. 735,159, dated August 4, 1903.

Application filed November 3, 1902. Serial No. 129,809. (No model.)

To all whom it may concern:

Be it known that I, FREDERICK H. SCHWARK, a citizen of the United States of America, residing at Bonfield, in the county of Kankakee and State of Illinois, have invented certain new and useful Improvements in Corn-Shock Compressors, of which the following is a specification.

My invention relates to certain new and useful improvements in corn-shock compressors; and its object is to produce a device of this class which shall work more effectively than any device heretofore in use and which shall be simpler and cheaper to construct and easier to operate.

To these and certain minor ends my invention consists in certain novel features of construction clearly illustrated in the accompanying drawings and described in this specification.

In the aforesaid drawings, Figure 1 is a perspective of my improved device in use, the figure showing a shock in dotted lines. Fig. 2 is a perspective of the device at the beginning of the tightening operation. Fig. 3 is a similar view of the device at a later stage in the tightening operation, and Fig. 4 is a central longitudinal section of the device.

Referring to the drawings, A is a shaft, of wood or metal, as may be desired, provided with a point a, adapted to be forced into a shock of corn or other grain. This shaft is adapted to support the device upon the shock. A collar B is provided at the end of the shaft 35 A opposite to said point. This collar forms a shoulder b. A circular plate C, preferably of wood, surrounds the shaft A and is held against the shoulder b by a collar D. The plate C is provided with two metallic plates c at its center to prevent undue wear of the plate C upon the collars D and B, which are preferably metallic. A handle E projects through a suitable perforation in the shaft A and is adapted to rotate the same. A cord F passes 40 through a suitable perforation a' in the shaft A and is held in place by a knot f. The cord F is of sufficient length to easily pass around a large shock, leaving a long loose end.

The operation of the device is substantially 45 as follows: The point a of the shaft A is driven into the corn-shock at the height at which it is desired to compress said shock. The cord or rope F is passed around the shock, as shown in Fig. 1, and the end is

doubled to form a loop f', which is carried 55 over the shaft A and under that portion of the rope F extending from the knot around the corn-shock, as shown in Fig. 2. Holding this loop F loosely under the strand of rope, the handle E is turned, thereby rotating the 60 shaft and bringing the loop f' between the main strand of the rope and the shaft A, as shown in Fig. 3. This secures the loose end of the rope to the shaft, and the handle may be then continuously turned around, winding up 65 the rope from both ends upon the shaft and compressing the corn-shock. The friction between the two strands of the rope F and the rim of the plate C is such that there is no tendency for the handle to be reversed by 70 the pull of the rope upon it. To secure this result, the plate C is made of large diameter, and its edge is made broadly convex, so that a large surface is pressed upon by the rope. I therefore am able to dispense entirely with 75 any other means for locking the device to prevent the shock from spreading after compression. A further advantage of this type of device lies in the fact that the rope is 80 equally pulled in at both ends instead of from only one. This produces a much easier pull, and a device utilizing its force in this way is much easier to operate than a device by which only one end of the rope is pulled at once.

I realize that considerable variations can 85 be made in the details of this construction, and I do not, therefore, desire to limit myself to the specific form herein set forth.

I claim as new and desire to secure by Letters Patent—

The combination with a shaft and a point thereon, of a handle secured to the shaft, a tightening-cord also secured to the shaft, a circular plate rotatable on said shaft and adapted to have frictional contact with said 95 cord when in place upon the corn-shock, said plate being so shaped as to have a large surface in contact with the cord, whereby the friction alone prevents retrograde rotation of the shaft, substantially as described.

In witness whereof I have signed the above application for Letters Patent at Bonfield, in the county of Kankakee and State of Illinois, this 29th day of October, A. D. 1902.
